UNITED STATES PATENT OFFICE

2,267,144

VENDING MACHINE

Louis Steiner, New York, N. Y., assignor to U-
Need-A-Pak Products Corporation, Brooklyn,
N. Y., a corporation

Original application June 28, 1938, Serial No.
216,270. Divided and this application Decem-
ber 28, 1939, Serial No. 311,298

3 Claims. (Cl. 312—42)

This invention relates to vending machines. It is particularly directed to vending machines having a plurality of chutes to stock different brands of cigarettes or other merchandise. This application is a continuation in part of applicant's co-pending application Serial No. 112,011, filed November 21, 1936, for Vending machines, and a division of copending application Serial No. 216,270 filed June 28, 1938, by applicant, and patented May 13, 1941, as Patent No. 2,241,489.

It is well known that some brands of cigarettes sell more slowly than others. Vending machines for brands of cigarettes coming in packages of substantially the same dimension, have heretofore been provided with chutes of the same height, and of the same cross-sectional area, and in which the cigarettes of the various brands are stacked in the same way, usually lying flat on the front or rear faces. If the chutes containing the slow selling brands are filled, the cigarettes therein often become stale, and if these chutes are not filled, a waste of space results. If the chutes are disposed side by side, the machine is too wide, and if the chutes are placed one in back of the other, the machine is too deep, since the machines usually also carry chutes for dispensing matches in back of the cigarette chutes. It is therefore an object of my invention to overcome the above mentioned difficulty in cigarette vending machines, by providing the machine with wide and narrow chutes arranged in a row, the wider chutes for the faster selling brands receiving packages stacked therein, lying on their front and rear wide faces; and the narrow chutes for the slower selling brands receiving the packages stacked therein on their narrow side edges. With this construction more packages may be stacked in the wide chutes than in the narrow chutes. By arranging the wide and narrow chutes in a row, side by side, the entire machine may be reduced in width, while serving the same brands as in the wider machines, wherein all of the chutes are of the same horizontal cross-sectional area, and in which the cigarettes are all stacked in the same way.

A further object of this invention is to provide in a machine of the character described, having pull bars controlled by insertion of a coin or coins into the machine, for pushing cigarettes from the chute to a discharge chamber, and locking means, disposed between the bars, to prevent more than one bar from being pulled at one time, wide and narrow chutes for the fast and slow selling brands of cigarettes, respectively, arranged alternately in a single row, whereby

the pull bars may be centered with respect to the chutes, and yet be spaced equally apart one from the other, to accommodate said locking means, and to facilitate manipulation of the draw bars.

Another object of this invention is to provide in a vending machine of the character described, highly improved locking means to prevent more than one draw bar from being pulled at a time to dispense a package of cigarettes.

Yet another object of this invention is to provide a neat, compact and rugged vending machine of the character described, which shall be relatively inexpensive to manufacture, easy to operate, positive in action, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

25 In the accompanying drawings, in which is shown one of the various possible illustrative embodiments of this invention,

Fig. 1 is a front, elevational view of a vending machine embodying the invention, with part of the front wall broken away to show the interior construction;

30 Fig. 2 is an enlarged, cross-sectional view taken on line 2—2 of Fig. 1;

Fig. 3 is a side, elevational view of the improved vending machine, with part of the side wall broken away to disclose the coin controlled mechanism;

Fig. 4 is a cross-sectional view taken on line 4—4 of Fig. 2;

40 Fig. 5 is a cross-sectional view taken on line 5—5 of Fig. 1;

Fig. 6 is a view similar to Fig. 5, but showing one of the pull bars pulled forward;

Fig. 7 is an enlarged, cross-sectional view taken on line 7—7 of Fig. 3;

Fig. 8 is a partial, top plan view of the pull bars and locking mechanism, with one of the pull bars drawn forwardly; and

Fig. 9 is a cross-sectional view taken on line 50 9—9 of Fig. 8.

Referring now in detail to the drawings, 10 designates a vending machine embodying the invention, for vending various brands of cigarettes or other packages or articles. The same comprises an outer casing 10a, having a rear wall 11,

side walls 12, and a front wall 13. Wall 13 has an upper wall portion 14, and a lower wall portion 15. Wall portion 15 is formed with an elongated discharge opening 16, and with a horizontal row of equally spaced vertical slots 15a above said discharge opening.

Fixed within the casing 10a in any suitable manner, is a box or member 18 made of sheet metal, and having a bottom wall 19 disposed just below the discharge opening 16, a rear wall 20 disposed adjacent the rear wall 11 of the casing, side walls 21, parallel to the side walls 12 of the casing, and a front wall 22 disposed adjacent the front wall 15 of the casing. Said front wall 22 is formed with an opening 23, substantially registering with the opening 16 in front wall 15.

Disposed within the bottom of the box 18 is a curved member 25, extending from the front edge of bottom wall 19, to the upper portion of rear wall 29, forming a dispensing chamber 18a, for the purpose hereinafter appearing.

The front wall 22 has a top flange 27 extending toward the rear wall 20. Fixed to the flange 27 and the side walls 21 of the box 18, as by spot welding or in any other suitable manner, is a member 28 having a horizontal wall 29 contacting said flange and extending rearwardly toward the rear wall 20. Extending downwardly from the horizontal wall 29, is a vertical wall 30, from which there extends a forwardly and downwardly inclined wall 31. Extending upwardly from the wall 29 is a vertical wall 32, substantially aligned with the front wall 22 of box 18. Wall 29 is formed with a plurality of parallel, equally spaced slots 34 extending from front to rear, for the purpose hereinafter appearing. The wall 32 is formed with a plurality of openings 33, aligned with the slots 34 in wall 29, and registering with the slots 15a in the front wall 15.

Mounted on the wall 29 is a row of vertical, alternatingly wide and narrow chutes 37 and 38, respectively, for cigarette packages 39 or the like prismatic packages or articles of similar size and of greater width than thickness.

As shown in the drawings, the chutes are of two kinds, to wit: wide chutes 37 and narrow chutes 38. The chutes are arranged side by side in a row, and the narrow chutes alternate with the wide chutes, for the purpose hereinafter appearing. The chutes are of the same depth from front to rear, being of a depth somewhat greater than the height of the packages. Each chute has a rear wall and side walls and inwardly extending flanges at the front. The side walls of adjacent chutes may be in contact. The wide chutes have a width somewhat greater than the width of the packages, and the narrow chutes have a width somewhat greater than the thickness of the packages.

It will be noted that in the chutes 37, the packages are stacked flat on their wider front or rear faces, with said front and rear faces in horizontal position. In the chutes 38, the packages are stacked on their side edges, with the narrow sides of the packages in horizontal position.

It is well known that some brands of cigarettes sell more slowly than others. In a vending machine in which slow selling brands are vended as well as fast selling brands, if the chutes were all of the same width and stacked full, all the chutes would have the same number of packages, and the chutes containing the slow selling brands would not empty as quickly as the chutes con-

taining the fast selling brands, causing the slow selling brands of cigarettes to become stale. If the chutes with the slow selling brands were not filled, a waste of space would result. This difficulty is overcome by providing chutes of wide and narrow widths so that the narrow chutes contain a lesser number of packages than the chutes of greater width.

With such construction, there is a greater choice in the number of cigarettes of each brand which may be stocked in the machine, while filling all of the chutes. Each chute can contain only one brand of cigarettes. If each wide chute 37 can contain twenty packages of cigarettes, and each narrow chute 38 can contain twelve packages of cigarettes, each brand may be stocked in multiples of twenty or multiples of twelve, up to the number of said chutes in the machine. Each brand may also be stocked in a number equal to any multiple of twenty (up to the number of chutes 37 in the machine), plus any multiple of 12 (up to the number of chutes 38 in the machine). Thus, if one chute 37 is filled with a brand, there are twenty packages of said brand in the machine; if two such chutes are filled with one brand, forty packages, and so on. If one chute 38 is stocked with a certain brand, there are twelve packages, two chutes 38, twenty-four packages, and so forth. Furthermore, one brand may be stocked in one chute 37 and one chute 38, making a total of thirty-two packages, or two chutes 37 plus one chute 38, making fifty-two packages, or one chute 37 and two chutes 38, making forty-four packages, and so forth.

A wide range in the number of packages of any brand may thus be stocked in the machine while filling each chute with one brand only. The machine having wide and narrow chutes is more compact and smaller in dimension and cheaper to construct. It will be readily seen that if all of the chutes were of the width of chute 37, the entire machine would have to be considerably wider.

Means is provided for pushing the bottommost package in each chute out of the chute to the dispensing chamber 18a in box 18. To this end, the rear walls of the chutes 37 are cut away at the bottom, as at 40, at least to a height equal to the thickness of one of the packages 39. The rear walls of the chutes 38 are cut away at the bottom, as at 41, to a height at least equal to the width of one of the packages 39.

Slidably mounted on the wall 29 of member 28, are a plurality of parallel, horizontal draw-bars 42, there being one bar for each chute, and said bars being equally spaced apart and centrally located with respect to each chute.

Each bar 42 has a straight horizontal portion 43 extending through one of the slots 33 and the slot 15a registering therewith. The lower edge of portion 43 is disposed within one of the slots 34. Said portion 43 has a finger engaging portion 44 at its front end. Each draw-bar 42 is provided adjacent its rear end with a thickened rear wall 46 and top wall 47. The lower edge of wall 46 contacts the top surface of wall 29 on opposite sides of the slot 34. Extending downwardly from the rear end of the bar 42 is a hook portion 48. Said portion 48 is thicker than portion 43 and contacts the underside of wall 29 on opposite sides of the slot 34.

As shown in Figs. 4 and 5, the lowermost package 39 normally rests on portion 47 of the bar. In such position, the lowermost package is

above the cut-out 40 or 41, and cannot fall or be pushed or pulled rearwardly out of the chute.

Mounted on the sides walls 21 of the box 18, and traversing the chamber 18a, is a horizontal shaft 50. Said side walls 21 are formed with similar, aligned arcuate slots 51 having centers of curvature at the axis of the shaft 50. Traversing the chamber 18 is a second shaft 52 having the ends thereof projecting within the slots 51. Shafts 50 and 52 are interconnected by links 52a. Mounted on the end of shaft 50 are torsion springs 53, each having one arm engaging the front wall 22 of the box 18, and another arm engaging the shaft 52, to normally move said shaft rearwardly to the rear ends of the slots 51. The hook portions 48 of the draw-bars 42 are adapted to engage the shaft 52, so that upon pulling any of the draw-bars forwardly, the shaft 52 is moved forwardly and somewhat upwardly being guided by the slots 51.

When a draw-bar is pulled to its forwardmost position, the packages in the chute associated therewith will drop onto wall 29. When the draw-bar is released, the springs 53 will push shaft 52 rearwardly to pull back the draw-bar, and push the lowermost package of cigarettes rearwardly, out of the chute, onto the wall 25 where it is guided to the bottom of discharge chamber 18a. The person purchasing the cigarettes may then insert his hand through the registering openings 16 and 23, into chamber 18a, to take out the package.

Means is provided to cover the cut-out openings 40 and 41 so that a person cannot obtain a package by inserting his hand through the chamber 18a. To this end, there is fixed to the side walls 21 of the box 18, a horizontal shaft 56, disposed adjacent the rear walls of the chutes and above the cut-outs 40, 41. Pivoted to the shaft 56 is a plate 57 adapted to cover said cut-outs.

Fixed to the ends of shaft 56 are links 52, interconnected by links 59 to the shaft 52. When no draw-bar is pulled out, and the shaft 52 is in its rearmost position, links 58 lift the plate 57 to uncover the cut-outs 40, 41. Since no package is entirely below said cut-outs, when the draw-bars are in normal position, no package can be removed through the chamber 18a. When a draw-bar is pulled forwardly, however, to permit the packages in the chute to drop to wall 29, the shaft 52 is pulled forwardly to pull down on the links 59, which in turn, pulls down on the links 58 to lower the plate 57 into position covering the cut-outs 40, 41. When the draw-bar is released, to push a package of cigarettes out of its chute, the plate 57 is again lifted to permit the package to be pushed rearwardly onto the curved wall 25.

Means is provided to prevent more than one bar at a time from being pulled forwardly. To this end, there is disposed on opposite sides of each draw-bar, a flat, horizontal, locking plate 62, pivoted at its rear end to the wall 29, by a vertical pivot 63. The forward ends of each plate 62 may be supported by a flange 64, stuck from wall 29, and disposed parallel to and below said wall 29.

Looking at Fig. 1, it will be seen that all of plates 62 are similar and that there is one locking plate between each pair of adjacent draw-bars 42, and a locking plate on the outer side of each of the end draw-bars. When no draw-bar is pulled forwardly, the locking plates have a slight pivotal movement about their pivot pins

63. However, when any draw-bar is pulled forwardly, the hook portion 48 thereof moves between the adjacent edges 67 of a pair of adjacent locking plates, moving all the other locking plates into contact, so as to prevent any other draw-bar from being pulled forwardly until the first draw-bar is released.

By alternating the wide and narrow chutes 37 and 38, the draw-bars 42 may be centered with respect to the chutes, and yet be equally spaced one from the other. With such construction, furthermore, the locking plates 62 may be of similar dimension.

Any suitable coin controlled means may be provided for controlling the draw-bars 42, such for example, as is illustrated in my Patent No. 2,083,928 issued on the 15th day of June, 1937. The coin controlled means may operate with any number of coins.

20 For the purpose of illustration, there is shown in the drawing, coin controlled means operated by a single coin. To this end, there is fixed to one of the side walls 21, a plate 70, disposed in a vertical plane and having bosses 71 in the corners thereof contacting said side wall. Said plate is fixed to the side wall 21 by screws 72 passing through said bosses. Plate 70 is formed on the outer face thereof with a longitudinal, horizontal through slot 71a. Said plate 70 is furthermore formed with a horizontal slot 83, registering with said slot 71a. The adjacent side wall 21 is formed with a slot 21a registering with slot 73.

Slidably mounted in the slot 71a is a slide plate 75. Fixed to the front face of plate 70 are a pair of vertical bars 70a to hold the plate 75 within the slot 71a. Fixed to the front end of the plate 75 is a stud shaft 76, projecting through slots 73 and 21a. Pivoted connected, as at 78, to the link 52a, is a link 80, formed at one end with a sleeve 81 passing through slots 73, 21a and rotatably receiving the stud shaft 76.

It will now be understood that when any draw-bar is pulled forwardly, the slide plate 75 will be pulled forwardly therewith, if a coin is inserted, as will be explained hereinafter.

Extending upwardly from the plate 70 is a coin chute 70b of any suitable construction, terminating at the front of the machine where a coin can be inserted. Plate 70 is formed with a vertical slot 70c at the lower end of the chute 70b and disposed above the slot 71a. Said plate 70 is furthermore formed with a vertical slot 70d in the same plane as the slot 70c, but located forwardly of said slot.

60 The plate 75 is formed with a horizontal through slot 83. The forward end of the slot 83 is widened or extended downwardly, as at 84, forming a ledge or edge 85, for the purpose hereinafter appearing. Said plate 75 is furthermore formed with aligned, vertical slots 87 and 88, communicating with the horizontal slot 83. In the rear position of the slide plate 75, the slots 87 and 88 are aligned with the slot 70c, so that a coin inserted into the chute 70b will drop down through the slots 70c, 87, pass the slot 83, and fall into the slot 88. In such position, the top of the coin will be substantially tangent to the main portion of the slot 83, and covering the ledge or shoulder 85.

65 Pivoted at one end to one bar 70a is a lever 90. Said lever is connected at its opposite end by a spring 91 to the other bar 70a. Spring 91 tends to pull the lever 90 downwardly. The 70 lever 90 has a projection 92 extending into the

slot portion 84, at the level of the shoulder 85. In such position, no bar can be pulled forwardly if a coin has not been inserted into the coin chute, because the slide 75 cannot be pulled forwardly due to engagement of the shoulder 85 with the projection 92 of lever 90.

However, when a coin is inserted into the coin chute 70b, and drops to the slot 88, the forward portion of the coin provides a ramp to engage the projection 92, to lift the lever as a draw-bar is pulled, and permit the slide to be moved forwardly. As the slide is pulled forwardly, the coin drops through the slot 70d to any suitable coin box. Upon release of the draw-bar a package is ejected.

Although the machine has been described as a cigarette vending machine, it will be understood that packages or articles other than packages of cigarettes, may be vended therewith.

Between the row of chutes 37, 38 and the rear wall of the casing are chutes 100 containing matches, and provided with any suitable means (not shown), such as shown in my Patent No. 2,076,750, issued April 13, 1937, to dispense the same.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying

drawings is to be interpreted as illustrative and not in a limiting sense.

Having thus described my invention, I claim as new and desire to secure by Letters Patent:

5 1. In a vending machine, a casing, a unit therein comprising a row of aligned, parallel upstanding, closely adjacent, alternatingly wide and narrow chutes of the same height, said chutes having side and rear walls and being of the same depth from front to rear, the horizontal distances between centers of adjacent chutes being equal, all of the wide chutes being of equal width, and all of the narrow chutes being of equal width, and means within said casing to support said unit.

10 2. In a vending machine, a unit comprising a row of aligned, parallel upstanding, alternatingly wide and narrow chutes of the same height, said chutes having side and rear walls and being of the same depth from front to rear, all of the wide chutes being of equal width, and all of the narrow chutes being of equal width, and each chute being contiguous to adjacent chutes.

15 3. In a vending machine, a row of aligned, parallel upstanding, alternatingly wide and narrow chutes of the same height, said chutes having side and rear walls and being of the same depth from front to rear, all of the wide chutes being of equal width, and all of the narrow chutes being of equal width, and each chute being contiguous to adjacent chutes the side and rear walls of each chute being fixed relative to each other.

LOUIS STEINER.
